WILHELM BOCK AND HOWARD W. MATTHEWS, OF LANSDALE, PENNSYLVANIA, AS
SIGNORS TO DEXDALE HOSIERY MILLS, OF LANSDALE, PENNSYLVANIA, A COR-
PORATION OF PENNSYLVANIA

ART OF KNITTING AND IN KNITTING MACHINES

Application filed January 3, 1928. Serial No. 244,089.

This invention is concerned with production of knit fabrics, more particularly on flat knitting machines; and also with improvements in such machines.

Amongst the objects of our invention are to enable more rapid production of knitted fabric than possible heretofore on flat knitting machines as ordinarily constructed; to effect accurate distribution or apportionment of pre-measured yarn between the needles of the machine with predetermination of absolute uniformity in the fabric loops; and to enable changes or graduation in the size of the fabric loops in successive courses of the knitting with assurance against variation as between the individual loops constituting each of such courses.

In carrying out our improved method, we initially measure out a definite length of yarn for each course of the knitting incidentally to feeding, and subsequently effect its apportionment between the needles as the fabric loops are drawn. For the first of these two steps we rely upon sinkers to depress the yarn at intervals between groups of the knitting needles; while the second step is accomplished through cooperation of knock-overs individually associated with the needles as the latter recede to form the fabric loops. With this arrangement, it is possible to dispense with the dividers and actuating mechanism customarily employed between sinkers for yarn apportionment in flat knitting machines to the end that the operation of loop formation is considerably speeded through saving of the time interval ordinarily required for functioning of the parts referred to. High speed operation of flat knitting machines is further facilitated in accordance with our invention through employment of rotary means throughout in lieu of reciprocating parts to actuate the various instrumentalities which cooperate in the knitting cycle.

Provision is also made for compensative bodily shifting of the needles and the knock-overs relative to the sinkers in determining initial measuring of more or less yarn for each course of the knitting and subsequent

uniform drawing of proportionately larger or smaller fabric loops by the needles.

How the foregoing and other advantages may be readily realized in practice will be manifest from the detailed description which follows of the typical embodiment of this invention shown in the drawings, whereof Fig. I is a part cross sectional elevation of our improved knitting machine.

Fig. II is a part plan view of the machine in accordance with the arrows II—II in Fig. I on a somewhat larger scale.

Fig. III is a part front view of the machine with some portions broken away and others in section.

Figs. IV and V are detail sectional views taken as indicated respectively by the arrows IV—IV and V—V in Figs. II and III.

Fig. VI is a detail plan section taken as indicated by the arrows VI—VI in Fig. V.

Fig. VII is a detail sectional view in accordance with the arrows VII—VII in Fig. III.

Figs. VIII to XIV inclusive are fragmentary views showing successive steps in the formation of fabric loops in accordance with our invention.

Fig. XV is a diagrammatic illustration viewed in the direction of the arrows XV—XV in Fig. IX showing how the yarn is measured by the sinkers.

Fig. XVI is an illustration similar to Fig. XV showing the measured yarn lying on the tops of the kock-over bits ready to be apportioned between the needles.

Figs. XVII and XVIII are views looking as indicated respectively by the arrows XVII—XVII and XVIII—XVIII in Figs. XI and XII.

Figs. XIX and XX are diagrammatic illustrations on a magnified scale showing the cooperation of the knitting instrumentalities incidentally to varying the size of the fabric loops in accordance with our improved method.

As herein shown, the machine comprises a head 21 supporting two needle banks 22, 22 (Fig. III), said head having an integral depending shank or tongue 23 which is confined to reciprocation up and down between 100

flanged antifriction rollers in a horizontal supporting guide bar 24. At opposite sides of its lower end the tongue 23 carries projections 25, 26 adapted to cooperate with opposing rotary cams 27, 28 respectively during ordinary knitting and during the fashioning phases of the knitting. As shown in Fig. III, the cams 27, 28 are set side by side upon a common longitudinally extending shaft 29 journalled both for rotation and axial sliding in suitable bearings of the transverse frames 30, 30 of the machine. The means for shifting the shaft 29 for selective operation of the cams 27, 28 may be of the type shown and described in a copending application filed September 12, 1927, Serial No. 218,971. From Fig. I it will be observed that the roller groove 27a of the cam 27 has inward deviations at diametrically opposite points; while Fig. VII shows that the cam 28 has but one. Thus for each rotation of the shaft 29 during ordinary knitting with the cam 27 in action, the needle head 21 is reciprocated twice with production of two fabric courses, whereas with the cam 28 in action during fashioning, but one course is produced. In effect this corresponds to speed reduction and affords ample time for functioning of the loop transfer mechanism which may be of the kind disclosed in the application supra. At one end, the needle guide bar 24 has a pivotal connection 31 with an arm 32 secured to a rock shaft 33 extending between the transverse frames 30. The opposite end of the bar 24 is engaged, with capacity for horizontal sliding, in a transverse notch of a frontal rail 35 of the machine. Such sliding movement is imparted to the needle guide bar 24 for the purpose of measuring more or less yarn during feeding as later on fully explained, by means of a rotary cam 36 that is mounted on a shaft 37 extending parallel with the cam shaft 29 in a somewhat lower plane, said shaft 37 being also suitably journalled in the machine frames 30. The cam 36 has graduated rises 38 which are effective upon a roller 39 carried at the lower end of an arm 40 affixed to the rock shaft 33. Any suitable means may be employed to intermittently rotate the cam 36, for example, a ratchet wheel 41 and a pawl 42 controlled by the pattern mechanism such as shown in a copending application Ser. No. 218,971 filed by Wilhelm Bock, one of the present applicants, on Sept. 12, 1927.

Cooperating with the needles N of the heads 22 are sinkers S which are mounted for horizontal sliding movement in transverse grooves of a stationary support 43 extending between the machine frames 30 at the top. From Figs. II and III it will be observed that the sinkers S are distributed so as to depress the yarn at intervals along the needle banks 22 between groups, in the present instance of two needles each. The sinkers S associated with each needle bank 22 are

moved toward the needles by means including a revolving spiral cam 45 with oppositely-pitched wings 46, 47 which are effective upon the jacks J individually associated with said sinkers. As shown, the jacks J are mounted for independent movement on a common fixed fulcrum rod 48 and engage the rears of the sinkers in the manner clearly shown in Fig. I. With this arrangement the sinkers S are progressively advanced beginning first from one end of the series, and then from the other by the oppositely pitched wings 46, 47 of the spiral cam 45 synchronously, with travel of the yarn feeds whereof one is shown at F, back and forth across the needles, the throw imparted to the sinkers being however fixed, or in other words, between definite limits. There may, of course, be several of the feeds F each being secured to a slide 49 arranged to be reciprocated under guidance of a longitudinal rod 50 by any appropriate mechanism (not shown) suitable to the purpose. Concerted return or retractive movement of the sinkers S is brought about by means of a projecting rotor vane 51 on a shaft 52 engaging the depending butts of said sinkers incidentally to rotation in the direction of the arrow in Figs. I and IV. The shafts 52, 53 of the rotor 51 and the spiral cam 45 have journal support in the transverse frames 30 of the machine, and are driven from the shaft 29 aforementioned through the medium of a transmission including intermeshing gears conventionally represented by dot and dash lines at 54, 55, 56, 57 and 58 in Fig. I.

During formation of the fabric loops, the beards of the needles N are closed through contact with the rounded frontal edges of presser bars 60, one such presser bar being provided for each needle bank 22, see Figs. II, III and VI. As shown in Figs. I and IV, each presser bar is made in two sections 60a, 60b meeting in an inclined plane, the upper section 60a being grooved transversely for lodgment of knock-over bits B having inclined shanks, and the lower section 60b acting as a keeper to hold said bits in assembly. It is to be particularly noted that there is a knock-over bit B for each needle N in the machine. In addition to the usual nibs b affording the horizontal loop-rolling ledges, the knock-over bits B have auxiliary upper nibs b' with notches intervening for engaging the knit fabric or web W as in Fig. VIII, for example, and holding it against rising with the needles N when the latter are elevated to yarn feeding position. At the ends, the lower sections 60b of the presser bars 60 are extended beyond the upper sections 60a, and machined to substantially square cross section (Fig. V) for guidance to horizontal movement in jaws at the outer ends of supporting arms 61, 62. As shown in Fig. III, there are two of the arms 61 respectively for

the remote ends of each pair of presser bars 60, and only one arm 62 which serves the contiguous inner ends of each such pair of presser bars. With reference to Figs. I and 5 II it will be noted that the arms 61, 62 reach forward over the tops of the spiral cam 45 and the rotor shaft 52 from a rock shaft 63 at the rear of the machine. A depending arm 64 secured to the rock shaft 63 carries a 10 roller 65 at its free end for cooperation with a second series of graduated circumferential rises 66 on the rotary cam 36 (Fig. I) lying in a plane to the rear of the rises 38 and distinguished in said figure by surface shading. 15 By the arrangement just described, slight vertical movement is imparted to the presser bars 60 for elevation and depression of the knock-over bits B concurrently with bodily inward and outward shifting of the needle 20 bar 21 for the purpose of varying the size of the fabric loops.

In performing the needle beard closing function, the presser bars 60 are reciprocated relative to the needles under guidance of the 25 jaws in the supporting arms, by rotary side groove cams 67-68 which are mounted on the shaft 51 and engage rollers 69 on arms 70 projecting rearward from the ends of the lower sections 60b of said presser bars. As 30 shown in Figs. II and III, the cams 67 are disposed adjacent the remote ends of each pair of the presser bars; while the cam 68 is double faced so as to serve contiguous ends of the presser bars, see also Fig. VI.

35 The operation of our invention is as follows: With the needles N dwelling temporarily in the elevated or feeding position of Fig. I, the yarn Y is laid across them by the feed F as shown in Fig. VIII, 40 above the lower nibs of the sinkers S which are concurrently advanced successively in synchronism with the travel of the feed under the dictates of the spiral cam 45 in the manner already understood, the yarn 45 being thereby depressed in the intervals between pairs of the needles as shown in Figs. IX and XV. The needles N are thereupon lowered bodily by the cam 27, and the sinkers S retracted at the same time in proper 50 phase relation by the rotor vane 51. During this stage in the cycle, the presser bars 60 dwell in the forward position to close the beards of the needles as in Fig. X and enable passage of the latter through the loops 55 of the previously formed course of the knitted web W. As the needles continue to descend, they carry down the length of yarn previously measured as a consequence of indentation by the sinkers S, to the level of the upper 60 nibs b' of the knock over bits B. This condition is depicted in the diagrammatic plan view of Fig. XVI. Thereupon, with still further descent of the needles N, the yarn is drawn over the upper nibs of the knock-overs 65 B, as shown in Figs. XI, XVIII, and, as a consequence, apportioned evenly between them, the free indentations previously formed by the sinkers yielding readily to partial absorption for the purpose explained. During the last described step, the presser bars 60 70 are retracted sufficiently by the rotary cams 67, 68 so that the upper nibs of the knock-over bits B are cleared and the needles permitted to draw the uniformly distributed bights of the yarn through the loops of the 75 preceding course of the knitted web W resting on the lower ledges of said knock over bits as shown in Fig. XII. In this connection it is obvious that the rotary cams 67, 68 may be so designed as to effect retraction of 80 the knock-over bits B in time to enable apportionment of the yarn to be effected as the new fabric loops are drawn over the lower ledges b of said knock-overs. Incident to formation of the new fabric loops, the needles N are lowered by the cam 27 in concert with advancement of the knock-over bits B by the cams 67, 68 with consequent rolling or knocking of the old fabric loops linked with the new ones, over the tops of the needles. As the action proceeds, the upper nibs b' of the knock-over bits take a position over the newly formed fabric loops as shown in Fig. XIII to restrain the web against the influence of the needles N incidentally to their 90 further elevation by the cam 27. Upon completion of the loop forming cycle, the several knitting instrumentalities assume the position of Fig. XIV which, it will be noted, is the same as in Fig. VIII, in readiness for initiation of a succeeding fabric course through feeding of the yarn Y.

When variation in the size of the fabric loops is desired, the pawl 42 (Fig. I) is permitted to pick the ratchet wheel 41 in accordance with the effect desired. As the peripheral rises 38, 66 of the cam 36 act concurrently on the rollers 39, 65 at the ends of arms 40, 64, it will be apparent that the needles N will be moved inward toward the sinkers S through attendant horizontal shifting of the carrier bar 24, and the presser bars 60 elevated through rocking movement imparted to the curved arms 61, 62. In Fig. XIX we have shown the normal relation of the needles N, the sinkers S and the knock-over bits B (corresponding to Fig. VIII) in full lines, and the shifted positions of the needles and knock-over bits for loop enlargement in dotted lines. Now since the throw of the sinkers S is fixed, i. e. since they always move back and forth between limits predetermined by the spiral cam 45 and the rotor vane 51, it will be seen that by virtue of shifting of the needles to the dotted position of Fig. XIX more yarn will be depressed between them with measurement of a greater length for the series. The proportioning of the various leverages involved in determining 110 loop variations is such that the movement 115 120 125 130

imparted to the knock overs B is definitely related to that of the needles so that the greater (or shorter) length of premeasured yarn is afterwards uniformly apportioned between the needles by draft over the upper nibs of said knock-overs B. This contention will be readily understood from Fig. XX (corresponding to Fig. XI) wherein, as in Fig. XIX, the normal relation of the needles N and the knock over bits B is shown in full lines, and their position for loop variation in dotted lines. By such compensative cooperation as between the needles and the knock-over bits relative to the sinkers and to each other, uniformity in the loops in any one course of the fabric is absolutely assured. The circumferential rises of the cam 36 (Fig. I) have been exaggerated considerably to serve the purpose of illustration, and, in practice, may be graduated as shown, or otherwise varied to suit any specific requirements.

The employment of continuously rotating parts to effect actuation of the knitting instrumentalities as herein described, is conducive toward operation of the machine at very high speeds with attendant increase in production. This consideration is further enhanced in view of the structural simplicity of our machine had by dispensing entirely with dividers and relegating the function ordinarily performed by them to the knock-overs, as well as by reliance upon a common means to actuate both the needle beard presser bars and the knock-overs.

Having thus described our invention, we claim:

1. In a flat knitting machine, a bank of needles, a guide confining the needle bank to reciprocatory movement, cooperating sinkers having a fixed throw, a stationary support for the sinkers, a series of knock-over bits over which the fabric loops are drawn, a pivoted support sustaining the knock-over bits with capacity for sliding movement toward and away from the needles, and an intermittently actuated rotary cam operative to shift the needle bank guide positionally relative to the sinkers for measurement by the latter of more or less yarn for each course of the knitting and to concurrently move the knock-over support compensatively for relative positioning of the knock-over bits to insure uniform drawing of correspondingly larger or smaller fabric loops.

2. In a flat knitting machine, a bank of needles, co-operating sinkers having a fixed throw, co-operating knock-over bits over which the fabric loops are drawn, and an intermittently actuated rotary cam with graduated rises instrumental in positionally shifting the needle bank relative to the sinkers in determining measurement by the latter of more or less yarn for each course of the knitting, said cam also having other rises instrumental in concurrently shifting the knock-

overs

over bits compensatively to insure uniform drawing of correspondingly larger or smaller fabric loops.

3. In a flat knitting machine, a bank of needles, co-operating sinkers having a fixed throw, co-operating knock-over bits over which the fabric loops are drawn, a rotary cam with graduated rises instrumental in positionally shifting the needle bank relative to the sinkers in determining measurement by the latter of more or less yarn for each course of the knitting, said cam also having other rises instrumental in concurrently shifting the knock-over bits compensatively to insure uniform drawing of correspondingly larger or smaller fabric loops, and means automatically controlled by pattern mechanism to intermittently rotate the cam.

4. In a flat knitting machine, a series of sinkers, a series of spring beard needles, a needle beard presser bar, a series of knock-overs carried by the presser bar, said knock-overs having loop-drawing ledges overhanging web holding notches, means for reciprocating the presser bar to effect closure of the needle beards incident to loop formation and to re-engage the fabric in the web holding notches of the knock-overs upon formation of each new course of loops, and means for positionally shifting the needles relative to the sinkers to predetermine measurement of more or less yarn and for concurrently positioning the presser bar compensatively to insure uniform drawing of correspondingly larger or smaller loops over the loop-drawing ledges of the knock-overs by the needles.

5. In a flat knitting machine, a series of sinkers, a series of needles, a series of knock-overs with loop-drawing ledges overhanging web holding notches, means for reciprocating the knock-overs to re-engage the fabric in their web holding notches upon formation of each new course of loops, and a rotary cam instrumental in positionally shifting the needles relative to the sinkers to predetermine measurement of more or less yarn, and for concurrently positioning the knock-overs compensatively to insure uniform drawing of correspondingly larger or smaller loops over their loop-drawing ledges by the needles.

6. In a flat knitting machine, a series of sinkers, a series of needles, a series of knock-overs with loop-drawing ledges overhanging web holding notches, means for reciprocating the knock-overs to re-engage the fabric in their web holding notches upon formation of each new course of loops, and means for positionally shifting the needles relative to the sinkers to predetermine measurement of more or less yarn, and for concurrently positioning the knock-overs compensatively to insure uniform drawing of correspondingly larger or smaller loops over their loop-drawing ledges by the needles.

7. In a flat knitting machine, a series of

needles, a series of sinkers numbering less than the needles and cooperating with them in measuring a definite length of yarn for each course of the knitting; individually associated knock-overs cooperating, incident to descent of the needles, to apportion the yarn premeasured by the sinkers; and means for changing the operative relation of the sinkers, the needles and the knock-overs, to determine measurement of more or less yarn and subsequent uniform compensative apportionment of such yarn into fabric loops.

In testimony whereof, we have hereunto signed our names at Lansdale, Pa., this 23d

15 day of December, 1927.

WILHELM BOCK.

HOWARD W. MATTHEWS.
